By Knight for city's

UNITED STATES PATENT OFFICE.

HUBERT WITTE, OF ST. LOUIS, MISSOURI, ASSIGNOR TO ST. LOUIS CAR COMPANY, OF ST. LOUIS, MISSOURI.

SIGN FOR STREET-RAILWAY CARS.

SPECIFICATION forming part of Letters Patent No. 762,108, dated June 7, 1904.

Application filed September 14, 1903. Serial No. 173,079. (No model.)

To all whom it may concern:

Be it known that I, HUBERT WITTE, a citizen of the United States, residing in the city of St. Louis, in the State of Missouri, have 5 invented certain new and useful Improvements in Signs for Street-Railway Cars, of which the following is a full, clear, and exact description, reference being had to the accompanying drawings, forming part of this 10 specification.

My invention relates to a sign for application to a street-car to indicate the line over which the car travels; and, briefly stated, it 15 consists in mechanism whereby a sign-apron 15 may be caused to travel in one direction under the action of a spring-roller and in the opposite direction through the medium of mechanical operating mechanism.

The invention consists in features of novelty 20 hereinafter fully described, and pointed out in the claim.

Figure I is a longitudinal section of a sign-casing with my sign illustrated therein. Fig. II is a vertical cross-section taken on line II 25 II, Fig. I. Fig. III is an enlarged interior view of the gear-casing and the ratchet-gear of my sign-operating mechanism shown therein. Fig. IV is a perspective view of my sign shown applied to the upper part of a street- 30 car.

1 designates a casing in which my sign is situated and in the front of which is a transparent sheet 2, preferably of glass, through which an insight into the casing may be seen.

3 is a door at the rear of the casing.

4 designates incandescent lamps supported in the casing 1 behind the transparent sheet 2.

5 designates a spring-roller journaled in 40 brackets 5^a, fitted to the end walls of the casing 1 in proximity to the front of said casing.

6 is an apron on which the names of streets are printed according to the lines over which a car equipped with my sign is likely to travel, 45 and this apron leads from the spring-roller 5 to a roller 7, to which the second end of the apron is secured, so that the apron may be wound onto either of the rollers 5 or 7.

8 is a toothed wheel fixed to the roller 7, and 9 is an endless chain that is mounted on 50 said toothed wheel.

10 is a gear-casing in which is mounted a toothed wheel 11, that receives the endless chain 9. Fixed to the shaft 12, on which the toothed wheel 11 is carried, is a ratchet-wheel 55 13, and secured to the outer end of said shaft is a crank-handle 14. (See Fig. I.)

15 is a dog provided with a pawl 16 for engagement with the ratchet-wheel 13 and having a handle 17, that extends to the exterior 60 of the gear-casing to be accessible by a person in operating the sign.

18 is a spring situated within the gear-casing to bear thereagainst and against the pawl 16, to which it is held by a stud 19, that projects from said pawl.

In the practical use of my sign the apron 6 is shifted in one direction when it is desired to expose to view the name of a certain street by turning the crank 14, which causes rotation of the toothed wheel 11 and ratchet-wheel 70 13. When this rotation takes place, the pawl 16 slips readily over the teeth of the ratchet-wheel, and the endless chain 9 is caused to travel to rotate the toothed wheel 8 and the 75 roller 7, to which said last-named toothed wheel is fixed. The apron 6 is thereby wound onto the roller 7 and off of the spring-roller

5, thereby at the same time increasing the tension of the spring in said spring-roller. When 80 it is desired to reverse the movement of the apron 6, the pawl 16 is released from engagement with the ratchet-wheel 13 by pressing the dog-handle 17 inwardly, and the spring action of the spring-roller 5 will then cause 85 the apron 6 to be wound onto said spring-roller and off of the roller 7, during which time the endless chain 9 will travel in a direction the reverse to its former travel, and the speed at which it moves may be governed by holding the crank-handle 14 to regulate its rotation in a direction retrograde to its former rotation.

I claim as my invention—

In a sign of the character described, the combination with the spring-roller, of a curtain se-

cured at one end to the roller, means for controlling the operation of the spring-roller comprising a casing, a ratchet-wheel within the casing, a pawl mounted within the casing for engagement with the ratchet-wheel and provided with an extension which passes to the exterior of the casing and a second extension,

and a helical spring surrounding the second extension and bearing against the pawl and the casing.

HUBERT WITTE.

In presence of—

A. DIEKMANN,
M. H. MURPHY.
